Richard Brown,

ATTORNEY

UNITED STATES PATENT OFFICE.

JOHN T. CROCKETT, OF CARTERSVILLE, KENTUCKY.

SUCTION APPARATUS.

1,276,495.

Specification of Letters Patent. Patented Aug. 20, 1918.

Application filed April 27, 1913. Serial No. 93,942.

To all whom it may concern:

Be it known that I, JOHN T. CROCKETT, a subject of the King of Great Britain, residing at Cartersville, in the county of Garrard and State of Kentucky, have invented certain new and useful Improvements in Suction Apparatus, of which the following is a specification.

This invention relates to improvements in suction apparatus of that type employed in connection with the treatment of boils, and the like, and it contemplates, primarily, the provision of a novel device of this nature which aside from performing all of the necessary functions incident to its use, in the above connection, comprises means whereby its entrance into the boil, or other affected part, is greatly facilitated.

Another object of the invention is to provide means to facilitate entrance of the ingress tube of the suction apparatus into the boil, and to thus prevent the skin about the boil being drawn over the ingress opening, such as would greatly impair the operativeness of the apparatus.

A still further object of the invention is to provide a device of the type in question that is extremely simple in construction, strong and durable in use, and highly practical both from the standpoint of the manufacturer and the standpoint of the user and which, it is believed, may be manufactured at a comparatively low cost.

Various other objects and advantages will become apparent during the continuance of the following description.

These objects are accomplished by such means as are shown in their preferred embodiment in the accompanying drawings, described in the following specification, and then more specifically pointed out in the appended claims.

In the accompanying drawings wherein like characters designate like parts through-out the several views;

Figure 1 is a side elevation showing the device as it appears prior to being associated with the part to be acted upon;

Fig. 2 is a view in longitudinal section taken through the device; and

Fig. 3 is a view in end elevation.

In the present embodiment, 10 designates the body of the suction apparatus, which is preferably in the form of an elongated tube 56 formed of glass, or like material constricted at one end to form an ingress tube or nipple

12 and provided, at its opposite end, with a removable plug 13. The said plug 13 has a coaxial bore 14 to each side of which are arranged air vents 15, the bore only receiving the piston 16, as illustrated in Fig. 2.

At one end the piston 16 carries a suction head 17 which fits snugly with the inner walls of the tube 10, while at its outer or other end it carries a suitably milled head 18, whereby it may be manipulated. The piston head 17 may be formed of any desirable material, but it is pointed out that stiff leather or the like is preferable. Likewise, the head 18 may be of any desired form and fashioned in any particular manner, since I do not limit myself to that particular configuration shown.

In connection with the suction apparatus above described, I employ novel means which facilitate the entrance of the nipple 12 into the boil, and which at the same time may be operated to remove the core, in the event that the latter is of a nature which cannot be sucked through the nipple 12. This attachment comprises generally, two complementary sections 19 and 20, respectively, which may be formed from blanks of metal, or by casting, if it is so desired. Each section comprises a handle 21, and a 85 tapered jaw 23, which extends oppositely to the handle 21. The body 22 is in turn provided with projecting ears 24, which when brought into overlapping engagement with the ears of the other section may be 90 pivotally connected with the latter ears, as at 25. Consequently, it will be noted that the sections 19 and 20 are held in pivotal relation, so that upon manipulation, jaws 23 may be brought into or out of engagement 95 with each other. Furthermore, by forming the sections from blank material, the material may be flexed transversely about its longitudinal axis, so that the sections when connected, provide a substantially circular 100 way therebetween, such as will permit of the free manipulation of the suction apparatus.

The operation of my invention is generally as follows:

When in the position as shown in Fig. 1, the tapered ends of the jaw 23 are in juxtaposed relation, such as will permit of their insertion into the boil or other part to be acted upon. The free ends of the handles 110 21 are then pressed lightly toward each other, such as will cause the spreading of the

2
jaws 23, and when this occurs, tube 10 may be moved forwardly so as to position the nipple 12 directly in the boil. Then by drawing outwardly upon head 18, the suction head 14, is drawn rearwardly within the tube 10, such as will create a partial vacuum in the forward portion of the tube, and thus draw the interior formation of the boil into the tube, by way of nipple 12. In the event 10 that the core of the boil is of such a nature that will not pass through the tube, the suction apparatus may be removed from the sections 19 and 20, and the latter manipulated so that the jaws 23 will grip the core 15 and thus draw the same from the boil.

From the foregoing, it is believed that the advantages and novel features of the invention will be understood, and therefore further detailed description is deemed unnecessary.

In reducing the invention to practice, it will be found that the form referred to herein as the most practical and preferred embodiment is the most efficient, but realizing that certain conditions will necessarily vary in concurrence with the adoption of the device, it is emphasized that various minor changes may be resorted to when required without sacrificing any of the advantages of 20 the invention, as defined in the appended claims.

Having thus fully described my invention, what I claim to be new and desire to secure by Letters Patent, is:—

1. In a device of the character described, 35 two handle members pivotally connected intermediate their ends, one end of each of said handle members being tapered to a point and thus forming opposed spreader jaws, said handle and said jaws being substantially semi-circular when viewed in cross section, and a suction apparatus slideable between said handle members and said jaws to coöperate with said jaws, as and for the purpose specified.

2. In a device of the character described, 40 two handle members substantially semi-circular when viewed in cross section, one end of each of said handle members being tapered to a point thereby forming a jaw, means pivotally connecting said handle members adjacent said jaws, and a suction apparatus including a movable plunger operable between said handle members and co-operating with said jaws, substantially as 45 described.

In testimony whereof I affix my signature in presence of two witnesses.

JOHN T. CROCKETT.
